UNITED STATES PATENT OFFICE.

JAMES J. CREADON, OF CHICAGO, ILLINOIS, ASSIGNOR, BY MESNE ASSIGNMENTS, TO
LITE PRODUCTS CORP., OF WILMINGTON, DELAWARE, A CORPORATION OF DELA-
WARE.

CURTAIN ROD.

Application filed October 12, 1921. Serial No. 507,192.

To all whom it may concern:

Be it known that I, JAMES J. CREADON, a citizen of the United States, residing at Chicago, in the county of Cook and State of Illinois, have invented new and useful Improvements in Curtain Rods, of which the following is a specification.

This invention relates to automobile side curtains which are provided with sections so arranged as to swing with the doors of the car, the invention relating more particularly to such door sections, and its object being to provide a structure by which the door sections will be held firmly closed and prevented from swaying open when the car is in motion.

With the object stated in view, the invention consists in a novel combination and arrangement of parts to be hereinafter described and claimed, and in order that the same may be better understood, reference is had to the accompanying drawings, forming a part of this specification.

In the drawings:

Figure 1 is an elevation showing the application of the invention; Fig. 2 is an inside view of one of the door sections; Fig. 3 is a similar view of another section; Fig. 4 is an enlarged vertical section on the line 4-4 of Fig. 1; Fig. 5 is an enlarged sectional detail on the line 5-5 of Fig. 3; Fig. 6 is a similar view on the line 6-6 of Fig. 2, and Fig. 7 is a perspective view of a socket piece.

Referring specifically to the drawings, 10 denotes a fragment of the body of an automobile provided with a top 11 of any suitable design. Fig. 1 shows one side of the body, the front door being denoted by the reference character 12, and the rear door by the reference character 13. A side curtain is shown on this side of the car, the same being provided with sections which are arranged to swing with the doors. It will be understood, 45 of course, that the other side of the car is to be similarly equipped.

The curtain section for the door 12 is denoted by the reference character 14, the same being provided with a transparency 14^a as usual. The curtain section has the usual enclosed top and bottom edge reinforcements 14^b, and it conforms in width to the width of the door, whereas its height is such that it completely encloses the space between the 55 bottom edge of the top 11 and the top edge

of the door 12. The curtain section 14 is therefore to all intents and purposes a continuation of the door 12. The bottom edge of the top 11 has a rabbet 11^a in which the top edge of the curtain section seats when the door 12 is closed, and which forms a stop for the curtain section, and a weather-proof joint.

The means for attaching the curtain section 14 to the door consist of two rods 15 which are located adjacent to the vertical edges of the curtain section, and are secured to the reinforced top edge thereof. The lower end of each rod is offset, as shown at 15^a and seats in a socket piece 16 embedded flush in the top edge of the door 12.

Each rod 15 is made in two sections, the lower section having the offset 15^a being provided with a top socket 15^b in which the lower end of the top section seats.

The curtain section 14 is also provided with two vertical brace rods 17 which are secured at the top to the upper ends of the rods 15 and fastened with the latter to the reinforced top edge of the curtain section. 80 Each rod 17 is in two sections which are adjustably connected by a turnbuckle 17^a.

The lower end of each rod 17 is detachably fastened to the door 12 by being passed through a vertical aperture 18 in a plate 19, 85 in which aperture it is held by a set screw 20 threaded into the plate. The plate 19 is secured to the inner face of the door 12 by screws or other suitable fasteners, and in order to obtain a better hold its side which is 90 contiguous to the door has a spur 19^a which is driven into the door.

The socket piece 16 has internal vertical ribs 16^a which fit in external grooves 15^c in the offset lower end 15^a of the rod 15 when the latter is inserted into the socket, this structure being provided for locking the rod against a rotary or twisting movement.

A door curtain section secured as hereinbefore described is strong and durable, and the attaching means enable the curtain section to be readily put up. The curtain section is held firmly closed against the top, and it does not sway open but is at all times held in weatherproof position. The attaching means cannot rattle, and they eliminate all curtain fasteners on the body of the car. The curtain section can be readily removed, and its firm position prevents the transparency 14^a from cracking. The turnbuckles 105 110

17^a enable the brace rods 17 to be tightened to take up all looseness and to keep the top of the curtain section tightly seated in the rabbet 11^a.

5 21 The attaching means of the curtain section 21 for the rear door 13 are the same as those of the section 14, with the exception that the rear rod 22 is curved to conform to the curvature of the rear edge of the said 10 section 21.

I claim:

1. The combination with an automobile door, of a curtain extending upwardly from the top thereof, rods secured at their upper 15 ends to the top of the curtain and detachably connected at their lower ends to the door, said rods being in sections which are detachably coupled, and brace rods extending between the top of the curtain and the top of 20 the door, and secured at their upper ends to the curtain and detachably connected at their lower ends to the door, said brace rods being

also in sections which are adjustably connected for maintaining the coupled relation of the first-mentioned rod sections.

25

2. The combination with an automobile door, of a curtain extending upwardly from the top thereof, rods secured at their upper ends to the top of the curtain and detachably connected at their lower ends to the door, 30 said rods being in sections which are detachably coupled, one of the sections having an end socket in which the other section seats, and brace rods extending between the top of the curtain and the top of the door, and secured at their upper ends to the curtain and detachably connected at their lower ends to the door, said brace rods being also in sections which are adjustably connected for maintaining the coupled relation of the first- 40 mentioned rod sections.

35

In testimony whereof I affix my signature.

JAMES J. CREADON.
